CLAIM

The ornamental design for a swiveling audio/video column, as shown and described.

DESCRIPTION

FIG. 1 is a perspective view of a swiveling audio/video column showing my new design;

FIG. 2 is a front elevation shown with the column and base aligned;

FIG. 3 is a back elevation corresponding to FIG. 2;

FIG. 4 is a left side elevation corresponding to FIG. 2, the right side elevation being a mirror image thereof; and,

FIG. 5 is a top plan view corresponding to FIG. 2.
